IRVING WOLFF, OF NEW YORK, RUSSELL P. MAY, OF BRONX, AND ABRAHAM RINGEL, OF BROOKLYN, NEW YORK, ASSIGNORS TO RADIO CORPORATION OF AMERICA, A CORPORATION OF DELAWARE

AUDITORIUM LOUD SPEAKER

Application filed August 3, 1928. Serial No. 297,218.

This invention relates to the loudspeaker art and deals more specifically with an auditorium loudspeaker.

It is well known that most loudspeakers radiate sound energy better in certain directions than in others. This directional characteristic of sound radiation is particularly noticeable, when the length of the wave being radiated is comparable with, or smaller than, the diameter of the effective radiating surface. In loudspeaker operation, this results in the higher tones of the audible range being propagated in the form of a beam from the loudspeaker, while the lower tones radiate so as effectively to cover a wide area. Obviously, therefore, in auditorium work unsatisfactory results are obtained with the usual loudspeakers due to the fact that a certain portion of the audible spectrum is transmitted in the form of a rather narrow beam, while the other portion of the spectrum is propagated in all directions.

It is an object of this invention, therefore, to give substantial uniformity of sound intensity over any desired area at all frequencies within the audible range.

Also, when two or more radiating surfaces are mounted alongside of each other, there are certain positions in space, where there will usually be a difference in the path length of the sound reaching the listener from the separate surfaces. This may result in bad interference between the sound waves emanating from each of the radiating surfaces unless care is taken properly to place them.

It is therefore a further object of this invention so to mount a plurality of sound radiating surfaces with respect to each other, that interference, due to a difference in path of the sound emanating from each surface, is reduced to a minimum in the direction in which sound propagation is desired.

It is a further object of this invention to mount a plurality of sound radiating surfaces with respect to each other so that the path lengths of sound emanating from any one of these surfaces to a given point will be effectually the same at all angles in a horizontal plane. This result is made possible

by mounting the vibrating units in a vertical line.

Arranging the diaphragms in a vertical line leads to the additional beneficial result that the radiation is concentrated in a slightly diverging horizontal disc of a height about equal to the height of the cone line. This leads to a very desirable increase in sound intensity in this disc, thus making radiation useful which would otherwise be diffused upward and downward.

Further, it is an object of this invention to provide an auditorium loudspeaker having a plurality of vibrating surfaces each of which contributes to the required volume of sound for the auditorium, and which aid each other at low frequencies without objectionable interference between the sound waves produced by the separate radiating surfaces in other parts of the acoustic range.

It is a further object of this invention to provide an auditorium loudspeaker utilizing a plurality of sound radiating surfaces in which a predetermined sound pattern may be obtained by adjustment of the angular position of the radiating surfaces with respect to each other.

Finally, it is an object of this invention generally to improve loudspeakers of the type used for auditorium work.

These and other objects of the invention will be readily apparent to those skilled in the art from the following description taken in connection with the accompanying drawings in which:

Fig. 1 is a front elevation of an auditorium loudspeaker embodying the principles of this invention;

Figs. 2 to 5 inclusive are sectional views taken along lines 2—2 to 5—5 respectively of Fig. 1, each of these sectional views showing the angular relation of only one of the sound vibrating surfaces with respect to the baffle;

Fig. 6 is a side elevation of the device shown in Fig. 1;

Fig. 7 is a sectional view taken along the line 7—7 of Fig. 1;

Fig. 8 is a top plan view of the device shown in Fig. 9;

Fig. 9 is an elevational view of a modified form of the invention; and

Fig. 10 is a sectional view taken along the line 10—10 of Fig. 9.

Referring in detail to the drawings, the loudspeaker 10 is seen to comprise a non-vibratory support or baffle member 11 formed of wood, metal or any other suitable material. Mounted centrally of the baffle 11 in vertical alignment are four vibratory sound radiating devices 12, preferably of the cone type. Suitable driving units (not shown) are associated with each of the devices 12 in a manner well understood in the art, each of these devices being connected to a common amplifier or sound source. The size of the baffle is chosen of a proper magnitude to interpose a path from front to rear running around its edge, which path is long enough to prevent excessive reduction in low frequency response due to interference of sound radiated from rear with that from front.

We have found in actual practice that satisfactory results may be obtained with a baffle extending outwardly from the edge of the vibrating surface by an amount equal to $\frac{1}{4}$ to $\frac{1}{5}$ of the longest wavelength which the device is designed to reproduce. Thus, for a loudspeaker designed to reproduce 60 cycles as the lowest frequency, which corresponds to a wave length of about 16 feet, the baffle was made to extend about 3 feet outwardly from the edge of the vibrating surface.

By virtue of this structure, interference between sound vibrations emitted from the front and from the rear of the vibrating surfaces is eliminated at the lower frequencies, at which frequencies it has been found that the waves are propagated substantially in all directions, as distinguished from the beam effect manifest at the higher frequencies.

In order to obtain a uniform sound pattern for an auditorium, the radiating surfaces or cones 12 are disposed at different angles with respect to the baffle, each surface being adapted to furnish a certain predetermined sector of the room with sound material. Obviously, the number of radiating surfaces used, and the angles at which they are placed, may be varied widely as the acoustic conditions of the auditorium may require. We have found, however, that in most cases, four units mounted at the angles indicated in Figs. 2 to 5 inclusive give satisfactory results.

In order to mount the radiating surfaces 12 upon the baffle 11, the housings 13, which may be of either wood or metal, are provided, each housing being suitably shaped as shown in Figs. 1 to 6 to cause the front faces of the cone 12 to lie in the desired plane. Each of the housings 13 is provided with an extending edge 14 which is attached to the angle member 15 carried by the baffle 11. The union between the members 14 and 15 may be ef-

fected in any suitable manner such as, for example, by rivets or bolts 16.

Referring in detail to Figs. 8-10 there is shown a modified form of the invention in which each of the vibrating surfaces is mounted for rotation about an axis lying in the plane of the baffle member. To accomplish this result the baffle 111 is provided with the cut-out portions 112 arranged centrally of the baffle 111 in vertical alignment. Supporting members 113 shaped to fit the openings 112 are pivotally mounted at 114 as shown. Each of the members 113 has a cut-out circular portion to which is attached the edge of the vibrating surface 115. Each of the sound producing surfaces 115 is provided with suitable driving units, which are fixedly joined to it respective support 113 in the usual manner. It will thus be seen that the variable sound pattern may be provided for, by suitably adjusting the angle of the supports 113 with respect to the baffle 111. In accordance with a preferred embodiment of this invention we have adjusted the first and third vibrating surfaces from the top to lie in the plane of the baffle 111, while the second and fourth are displaced at an angle of 45° with respect to the baffle in opposite directions as shown.

It will be seen that when the supports are turned at an angle with respect to the baffle the lower frequencies will circulate around the edge of the supporting members 113 from the rear to the front sides and vice versa. This counteracts the useful effect resulting from the employment of baffle 111. We, therefore, provide the auxiliary baffle members 117 having circular side walls joined to the baffle 111 by any suitable means such as rivets or screws 117a. The opposite ends of the members 117 are covered by segmental portions 118 as shown in Fig. 8. It will be understood that the auxiliary baffles are mounted one on the front and one on the rear of 111 for each vibrating surface 115, depending upon the angular relation of the vibrating surface 115 with respect to the baffle 111. Under certain conditions, however, it may be found desirable to reverse the cones 115 in such a way that the portion which extends rearwardly of 111 is made to extend forwardly thereof, and vice versa. Accordingly, the auxiliary baffles may be provided with detachable means for joining them to the member 111 as required.

Obviously, many changes in the specific embodiments of the invention disclosed herein will readily suggest themselves to those skilled in the art. For example, the radiating units may be mounted in a vertical plane without being in exact alignment, or, alternatively they may be in alignment at an angle to the vertical. We therefore do not intend to be limited in the details of structure except as defined in the appended claims.

Having thus described our invention, we claim:

1. A loudspeaker comprising a supporting member, and a plurality of sound radiating elements in vertical alignment carried by said member, said sound radiating elements being arranged to radiate sound waves directly to the open air in directions substantially perpendicular to the line of vertical alignment and at angles to each other.

2. A loudspeaker comprising a baffle member, and a plurality of sound radiating elements carried by said member, each of said elements facing perpendicular to the vertical centre line of the baffle and at angles to each other.

3. A loudspeaker comprising a non-vibrating surface and a plurality of vibrating elements mounted thereon, said non-vibrating surface being of a size sufficiently great to prevent objectionable interference between the sound waves from the rear and the front of the vibrating elements, substantially over the range of the entire audible spectrum, and said vibrating elements being mounted to radiate sound waves in different directions all of which lie within an angle of less than 180°.

4. A loudspeaker comprising a non-vibrating surface and a plurality of vibrating diaphragms mounted thereon and directed in different directions, said non-vibrating surface lying in a single plane and being of sufficient size to constitute a baffle whereby material circulation of sound waves between the rear and front of the vibrating diaphragms is prevented over substantially the entire range of the audible spectrum.

5. A loudspeaker comprising a non-vibratory baffle member, said baffle member being substantially in a single plane, and a plurality of vibratory elements carried by said member and angularly disposed with respect thereto.

45 6. A loudspeaker comprising a non-vibratory baffle member, and a plurality of sound radiating bodies mounted on said member, said member extending outwardly from each of said bodies by a distance at least as great as one fifth of the longest wave length which said bodies are adapted to radiate, whereby to prevent circulation between opposite sides of said surfaces.

7. A loudspeaker comprising a non-vibratory baffle member, and a plurality of sound radiating elements mounted on said member at angles to each other, said member extending outwardly from each of said elements a distance at least one fifth as great as the longest wave length which said elements are adapted to radiate, whereby said member prevents circulation between opposite sides of said surfaces.

60 8. A loudspeaker comprising a plurality of sound radiating members adapted to radiate

sound vibrations from both the front and rear sides thereof, and a baffle member surrounding each of said members and serving to prevent interference between the sound vibrations emitted from the front and rear sides of said members, the entire surface of said baffle member being substantially in a single plane.

70 9. A loudspeaker comprising a plurality of sound radiating members adapted to radiate sound vibrations from both the front and rear sides thereof, and a baffle member surrounding each of said members and serving to prevent interference between the sound vibrations emitted from the front and rear sides of said members, each of said members being angularly disposed with respect to each other.

75 10. A loudspeaker comprising in combination a baffle member, a first radiating diaphragm angularly mounted thereon and adapted to radiate a maximum of sound energy over a predetermined area, and a second radiating diaphragm mounted at an angle different from said first mentioned angle with respect to said member and adapted to radiate a maximum of sound energy over an area not included in said first mentioned area.

80 11. A loudspeaker comprising in combination a baffle member, a first radiating element angularly mounted thereon and adapted to radiate a maximum of sound energy over a predetermined area, and a second radiating element mounted at an angle different from said first mentioned angle with respect to said member and adapted to radiate a maximum of sound energy over an area not included in said first mentioned area, said baffle being of sufficient size to prevent circulation of sound vibrations between the front and rear sides of each of said radiating elements.

85 12. A loudspeaker comprising a baffle member, and a plurality of sound radiating elements pivotally mounted with respect to said member, whereby said elements may be adjusted angularly with respect to each other.

90 13. A loudspeaker comprising a supporting member, and a plurality of sound vibrating elements in vertical alignment carried by said member, each of said elements being angularly adjustable with respect to each other.

115 14. A loudspeaker comprising a supporting member, and a plurality of sound vibrating elements in vertical alignment carried by said member, each of said elements being rotatable about an axis parallel to said member.

120 15. A loudspeaker comprising a baffle member and a plurality of sound radiating diaphragms pivotally mounted thereon.

125 16. A loudspeaker comprising a baffle member, and a plurality of sound radiating devices mounted on said baffle, each of said de-

5 vices being mounted in a different horizontal plane and disposed at a different angle with respect to said baffle, and each of said devices being designed to radiate sound waves substantially straight out in its horizontal plane and in different vertical planes.

10 17. A loudspeaker comprising a baffle member, and a plurality of sound radiating devices mounted on said baffle, each of said devices being mounted in vertical alignment and disposed at a different angle with respect to said baffle, and each of said devices being designed to radiate sound waves substantially straight out in its horizontal plane and in different vertical planes.

15 18. An acoustic device comprising a baffle, and a member having a sound radiating surface, said member being pivotally mounted with respect to said baffle.

20 19. A loudspeaker device comprising a member having a sound radiating surface, a supporting member, and means for pivotally mounting the first mentioned member in said supporting member.

25 20. An acoustic device comprising a loudspeaker having a sound radiating surface, a support for said loudspeaker, and means for adjusting the position of said loudspeaker in said support to vary the direction of radiation of sound waves from said sound radiating surface.
